UNITED STATES PATENT OFFICE.

CHRISTIAN F. WEEBER, OF ALBANY, NEW YORK.

RAIL.

1,077,236.

Specification of Letters Patent. Patented Oct. 28, 1913.

Application filed April 17, 1912. Serial No. 691,862.

To all whom it may concern:

Be it known that I, CHRISTIAN F. WEEBER, a resident of Albany, in the county of Albany and in the State of New York, have 5 invented a certain new and useful Improvement in Rails, and do hereby declare that the following is a full, clear, and exact description thereof.

My invention relates especially to rails 10 which are adapted to be used in building railroads.

In the case of rails hitherto used, the usual type of rail has been constructed by laying a series of rail sections one after another in alignment, and securing the adjacent ends of the sections together by means of fish-plates having bolts passing entirely through the fish-plates and through the rails. When the rails are laid in this manner, it is 20 necessary to leave a considerable space between the rail ends in order to allow for expansion with the rise in temperature of the rails. This manner of construction necessarily leaves a small depression between the 25 adjacent ends of any two rails. This depression, under the continual hammering of the rolling-stock, becomes deeper and deeper until the rail ends must, of necessity, be ground away to make the depression gradual 30 or until the rails are replaced. The presence of depressions of this character has a very detrimental effect upon the condition of the rolling-stock as the continual vibration and hammering in quick succession 35 tends to loosen the various parts of the rolling-stock and eventually cause breakages which may be the cause of serious accidents and require extensive repairs. Not only is this the case, but the continual jarring produced in this manner is a source of very 40 great discomfort to persons riding over railroads built in this manner. Furthermore, there is a tendency, when railroads are built in this way, especially where the railroad is 45 not used very frequently, to cause the rails to be cemented together with the fish-plates, owing to the rusting action of water upon the joints. When the rails have become cemented together, there is very great danger 50 of accident to passing trains owing to the fact that expansion of rails cemented together in this way is impossible, and, as a consequence, the rails spread. Again, there 55 is a continual tendency for the bolts passing through the rails and fish plates to become loosened, owing to the continual vi-

bration, until finally enough of the bolts have been jarred out of place to permit the rail ends to become displaced. In order to avoid some of these disadvantages, a type of 60 construction has been used in which the rail ends are welded together. This form of construction is very disadvantageous, however, in view of the fact that there is no room for expansion in case of an increase of the 65 temperature and owing to the fact that, as a consequence, accidents are likely to result. Furthermore, a railroad constructed in this manner is very difficult to repair. In both of these forms of construction, however, it 70 is necessary to entirely discontinue the operation of trains when it is found advisable to replace one of the rails with a new rail.

By means of my invention, I avoid all of the disadvantages above referred to. In 75 carrying out my invention, I avoid the occurrence of any depressions in the rails which could cause vibration or hammering. I also entirely avoid the use of bolts. There is, furthermore, a total absence of danger of 80 the rails becoming cemented together, and the railroad may be repaired at any time by substituting new rails without the necessity of discontinuing the operation of trains.

While my invention is capable of embodiment in many different forms, I have, for the purposes of illustration, shown only certain modifications thereof, these modifications being shown in the accompanying drawings, in which—

Figure 1 is a plan view of a railroad made in accordance with my invention; Fig. 2 is a vertical section of one of the composite rails; Fig. 3 is a similar section of the form of my invention shown in Fig. 2 but 95 equipped with an angle iron for street-car purposes; Fig. 4 is a vertical section of another form of rail made in accordance with my invention; Fig. 5 is a vertical section of a further form; Fig. 6 is a side elevation of 100 one of the locking straps used at the rail ends; Fig. 7 is a plan view of the rail sections at a joint, and of the strap for connecting the rail ends; Fig. 8 is a side elevation of Fig. 4.

In the form of my invention shown in Figs. 1 and 2, I provide a road bed 1 having located therein a series of ties 2 which may be of any desired construction. The ties 2 carry two lines of rails 3 in the usual 110 way, each of the lines of rails 3 being constructed of a plurality of rail sections 4.

The ends of the several rail sections may be squared or beveled as may be desired. All of the rail sections 4 are constructed exactly alike, but any one line of rail is produced by 5 laying a pair of the rail sections 4 side by side with their supporting bases directed in opposite directions and so that the rail sections on one side extend to the middle of the rail sections on the other side, as shown 10 in Fig. 1. By locating the rail sections in this manner, there is not at any point along the line a continuous joint extending entirely across one line of rails. Each of the rail sections may be constructed as shown 15 in Fig. 2, with a head 5, a web 6 and a base 7. Between the base 7 and the web 6, there is a flange or shoulder 8 extending in the opposite direction to that of the base 7. Preferably, though not necessarily, the bases 20 7 of the rail sections are supported directly upon the ties 2.

In order to hold the rail sections together, I provide a number of locking straps 9, made of single forgings, each of which has 25 at the time it is applied to the rails and before being locked in position, a pair of upwardly and preferably outwardly directed ears 10, a flat upper surface 11 to receive the base portion 7 of the rail sections, and 30 a central tongue 12. In the form of my invention shown in Fig. 2, the locking straps are provided between the tongue 12 and the flat surface 11 with shoulders 13 to receive and support the flanges 8 located upon the 35 rail sections. The use of the shoulders makes the central portions of the straps much stronger. Said flanges 8 fit directly over the shoulders 13 and fill in the space left between said shoulders and the top of 40 the tongue 12. These locking straps are preferably applied to the rails between every other pair of ties, though they may be applied more frequently or less frequently or in any other desired manner, provided they are used for holding the rail sections in position. After the straps 9 have 45 been applied to the rail sections 4, the upwardly directed ears 10 are turned inwardly over the edges of the rail bases 7, thereby locking the rail sections permanently in 50 position.

As shown in Fig. 6, locking straps 14 might be used instead of those previously described, the locking straps 14 being constructed in the same manner as those already described, but omitting the shoulders 13. Rail sections which are used in connection with straps of this character might be constructed the same as those already 55 described or might be so constructed that the shoulders 8 are on the same level with the bases 7. For securing the rail ends together, I provide special locking straps 14^a having bifurcated ends, so as to produce 60 at each end of the strap a pair of ears 14^b,

separated by a recess 14^c. Each of the rail sections is provided with a notch 14^d at one end of the rail section to receive one of the ears 14^b when it is bent over the edge of the rail base. It will be noted that the rail sections are laid so that one notched end of a rail section is adjacent to an unnotched end of the adjacent rail section. By this means, the proper expansion of the rails with increases of temperature is not interfered with. Rails constructed in this manner may be readily adapted for street-car lines by attaching to one side of the line of rails a horizontal bracket 15 by means of bolts 16, as shown in Fig. 3, or in any other desired manner. The brackets 15 are applied only to prevent the formation of ruts in the city streets. There is no pressure produced upon the brackets 15 by the operation of the railroad and the passage of the rolling-stock 80 over the rails. 85

As shown in Fig. 4, I have provided another modification of my invention in which the rail is constructed of a plurality of rail sections 16 having heads 17 and bases comprising outwardly directed flanges 18, and inwardly directed flanges 19. The composite rail rests upon the outwardly directed flanges 18 and the flanges 19, which together with the head 17 form an internal channel or recess 20 for receiving a locking bar 21 which is inserted in sections between the rail sections. As indicated in Fig. 8, the rail sections are arranged so that the sections on one side have round holes 22 for receiving bolts 23, while the rail sections on the other side are provided with slots 24 to receive said bolts. This method of connecting the rail sections together will permit an ample amount of expansion with the increases in temperature. The modification shown in Fig. 5 is constructed in the same manner as the modification shown in Fig. 4, except that instead of providing the squared channel 20 for receiving the rectangular bar or bars 21, there is provided a circular channel 25 for receiving, in sections, a series of longitudinal round rods 26. In both of these modifications shown in Figs. 4 and 5, the bases of the rail sections are clamped together by means of locking straps 27 located at intervals along the rails, and arranged so that their ends 28 are bent over the edges of the flanges 18. 100 105 110 115

In the operation of my invention, the form shown in Figs. 1 and 2 is put together in the manner which has already been described. When a train passes over a line of rail laid constructed in this manner any downward movement of the rail sections on one side would tend to cause simultaneously therewith, a lateral movement of the rail sections. This lateral movement would be limited by the consequent upward movement of the attached rail base 7, and by the lat- 120 125 130

eral pressure exerted from the adjacent rail sections on the other side of the line of rails, the lateral pressure in question being exerted through the presence of the flange 8 beneath the enlarged tongue 12. There is, consequently, a certain degree of cushioning effect in rails constructed in this manner. The action of the modifications shown in Figs. 4 and 5 is substantially the same, although the parts are connected together in a somewhat different manner. Owing to the fact that the base of the composite rail is, in its total width, much wider than the bases of rails previously used, a much more stable and stronger construction results.

By the use of my invention it will be seen that any depressions which may be located between the ends of adjacent rail sections will not result in the vibration and hammering of the rolling-stock, owing to the fact that there is an overlapping rail section which overlaps in every instance the two ends of the adjacent rail sections located alongside thereof. There is, furthermore, no tendency for the parts at any time to become cemented together, owing to the fact that there is to some extent a relative movement vertically between the heads 5 of the rail sections which are located alongside of each other. This continual movement would prevent any cementation between the contiguous rail sections located alongside of each other. At the same time, rails constructed in this manner are so arranged as to allow ample expansion and contraction in case of changes of temperature. Should one rail section become broken there is no danger of an accident to a passing train, owing to the fact that the remaining section will carry the train over the place where the rail section is broken until time has been given to replace the broken section by a new one. Furthermore, the replacing of the broken section can be carried out without any necessity for stopping the operation of the train service. Rails made in this manner may be very easily constructed, owing to the fact that all the rail sections are of exactly the same shape. The rail sections are, furthermore, so constructed that they may be rolled without difficulty in a rolling mill, there being no sharp internal angles which might be difficult to form.

The form of my invention shown in Figs. 1 and 2 is particularly advantageous because of the fact that it dispenses with the use of bolts and nuts.

While I have described my invention above in detail, I wish it to be understood that many changes may be made therein without departing from the spirit of my invention.

Claims:

1. A composite rail comprising rail sec-

tions placed side by side and a strap binding the rail sections together, said sections having inwardly directed flanges extending into recesses in the strap and said strap extending over the outer edges of the rail bases. 70

2. A composite rail comprising rail sections placed side by side and a strap binding the rail sections together by having its ends turned over the edges of the rail bases, 75 said sections having flanges extending into recesses in the strap.

3. A composite rail comprising rail sections placed side by side and a strap extending over the outer edges of the rail bases and binding the rail sections together, 80 said sections having inwardly directed flanges extending into recesses in the strap.

4. A composite rail comprising rail sections placed side by side and a strap binding the rail sections together by having its ends turned over the edges of the rail bases, 85 said sections having inwardly directed flanges extending into recesses in the strap.

5. A composite rail comprising rail sections placed side by side and a strap binding the rail sections together, said sections having inwardly and outwardly directed flanges extending into recesses in the strap. 90

6. A composite rail comprising rail sections placed side by side and a strap binding the rail sections together by having its ends turned over the edges of the rail bases, 95 said sections having inwardly and outwardly directed flanges extending into recesses in the strap.

7. A composite rail comprising rail sections placed side by side and a strap extending over the outer edges of the rail bases and binding the rail sections together, 100 said sections having inwardly directed flanges extending into recesses located over elevated shoulders in the strap. 105

8. A composite rail comprising rail sections placed side by side and a strap binding the rail sections together by having its ends turned over the edges of the rail bases, 110 said sections having inwardly directed flanges extending into recesses located over elevated shoulders in the strap.

9. A locking strap for rails comprising a forging having a recess to receive a rail and an end adapted to be bent over to lock the rail in position. 115

10. A locking strap for rails comprising a forging having recesses to receive rail sections and ends adapted to be bent over to lock the sections in position. 120

11. A rail having a notch near its end and a locking strap for the rail, comprising 125 a bar having an end adapted to be bent over to engage said notch.

12. A locking strap for rails comprising a forging having bifurcated ends adapted to be bent over to secure the rails in position. 130

13. The combination of a rail, comprising rail sections placed side by side, each of said sections having both an inwardly projecting flange and an outwardly projecting base, and an integral fastening adapted to engage both of said flanges and both of said bases for fastening the rails together.
14. A composite rail comprising rail sections placed side by side and overlapping one another, said sections having their entire supporting surfaces located at the side

of the upper traction surface of the composite rail, the supporting surfaces being located directly upon the ties, and binding straps located at points between the ties.

15

In testimony that I claim the foregoing I have hereunto set my hand.
